7 Claims. (Cl. 125—11)

(Granted under the provisions of sec. 14, act of
March 2, 1927; 357 O. G. 5)

This invention relates to an improved method of and means for dressing or forming the operative surface of grinding wheels employed in form grinding and more particularly to the formation of grinding wheels of the kind having a plurality of annular serrations or cutting edges for use in producing or finishing screw threads by a grinding operation.

It is known that if the profile of a grinding wheel of the kind referred to is formed in the axial plane section as an exact replica of the screw thread it is desired to produce or finish, the resulting thread will in certain cases be found to be inaccurate. The discrepancy is due to the fact that whereas the thread to be formed is a continuous helix, the operative surface of the grinding wheel consists of a plurality of serrations which are annular. The error increases with the helix angle and is more pronounced in the case of internal grinding owing to the increased overlap of grinding surface contact (commonly known as interference) on opposite sides of a plane containing the axes of the grinding wheel and the work.

It, therefore, follows that as true form is normally dressed in this plane, any form produced in the work other than in said plane must be to a more or less extent untrue.

This increased overlap results from the fact that the contacting surfaces of the wheel and work in internal grinding are both curved in the same direction, whereas in the case of external grinding and contacting surfaces are curved in opposite directions.

The object of the present invention is to provide grinding wheels of the kind referred to with annular serrations or cutting edges of such form as will produce a screw thread approximating more closely to the theoretically correct form than has so far been possible.

In forming or dressing grinding wheels of the kind herein referred to for use in internal or external form-grinding operations by means of a tool having a form-generating motion, the improved method consists in successively dressing the rotating grinding wheel with the tool at different angular positions about a fixed axis.

Where the radial or depth component of the form-grinding motion of the dressing tool is produced by means of a rotating cam the dressing tool, according to the present invention, will be mounted so as to be angularly adjustable about the rotational axis of the said cam.

In any case it is essential that the minimum distance between the point of the dressing tool

and the axis of the angular movement of the latter shall be equal to the core radius of the work in the case of internal grinding and to the major radius of the work in the case of external grinding.

The present invention may be conveniently applied to the type of wheel dressing apparatus described in British Patent No. 398,841 in which the dressing tool is carried by two relatively movable slides one of which has a traversing movement in a direction substantially parallel with the axis of the grinding wheel and is operated by a lead screw, whilst the other slide has a reciprocatory movement towards and away from the axis of the said wheel under the influence of a rotating cam the profile of which determines the depth component of the resultant motion of the two slides.

The form of the serrations or cutting edges in the axial plane section of the grinding wheel which is produced according to the present invention will in no case be the true thread form it is required to produce in the work but will be such as to produce the true form and will vary according to the diameter of the work and to the pitch and helix angle of the thread in any given case.

In the accompanying drawings:

Figure 1 is a view in end elevation of a movable headstock carrying the work-holder and the improved wheel dressing attachment for internal grinding.

Figure 2 is a plan view thereof.

Figures 3 and 4 are detail face and edge views respectively of the wheel dressing attachment.

Figure 5 is a sectional view of the same.

Figure 6 is a diagram illustrating the operation of the dressing tool.

Figure 7 is an enlarged detail cross-sectional view of one of the serrations on the grinding wheel.

Figures 8 and 9 are views similar to Figures 1 and 2 showing the application of the present invention for external grinding.

Like parts are designated by similar reference characters throughout the drawings.

Referring to the constructions shown in the drawings the work holder 2 and the dressing attachment 3 are mounted alongside each other in a headstock 4 fixed to a slide 5.

The grinding wheel 6 is rotatably mounted in a head, not shown, which is capable of movement across the bed 7 of the machine so that the wheel can be moved from its position with respect to the wheel dressing attachment 3, as

shown in full lines in Figures 1, 2, 8 and 9, to the operative or grinding position with respect to the work-piece 8, as shown in dotted lines in the same figures.

The slide 5 carrying the work-holder and the dressing attachment has a traversing movement along the bed of the machine, as by means of a lead screw 9, in a direction parallel with the rotational axis of the grinding wheel in either of the two positions of the latter.

The diamond holder 10 of the wheel dressing attachment is adjustably mounted in a carrier 11 which itself is adjustably mounted upon a slide 12 arranged for movement toward and away from the grinding wheel in a direction at right angles to the direction of movement of the headstock, i. e. in a direction substantially radial to the rotational axis of the grinding wheel.

The movement of the slide 12 in one direction is produced by means of a cam 13 fixed to a shaft 13^a rotatably mounted in the headstock. The cam bears against a stylus 14 fixed to the slide, and in the return direction in any suitable manner, as by means of a spring or weight neither of which is shown. The said slide 12 is carried by a plate 15 capable of a rocking movement about the axis of the said cam and is guided in its movement in the said plate by adjustable ball bearings as shown in Figure 3.

The movements of the slides 5 and 12 by the leadscrew 9 and cam 13 respectively take place simultaneously and are of such relative and respective extent as to cause the dressing tool to generate the form required in the grinding wheel in the manner hereinafter described.

The distance between the point 16 of the diamond and the rotational centre of the cam 13 when the latter is at its peak position with respect to the stylus 14, is important and will depend upon the core radius of the work-piece in the case of internal grinding operations and on the major radius of the work-piece in the case of external grinding operations. The construction and operation of the wheel dressing attachment is otherwise substantially the same for dressing wheels for internal grinding purposes as for those employed for external grinding.

For dressing grinding wheels for producing or finishing internal screw threads the relative arrangement of the cam and the diamond are as shown in Figures 1 and 3, that is to say, the diamond holder is adjusted in its carrier until the distance between the point 16 of the diamond and the rotational axis of the cam 13 when the latter is at its peak with respect to the stylus 14 is equal to the core radius of the work to be ground.

For the dressing operation the grinding wheel head is moved to bring the grinding wheel 6 into the dressing position shown in full lines at the right-hand of Figure 1, this position being determined by means of a stop which is adjustable for wheels of different diameters.

The grinding wheel 6 is first dressed in the normal way with the diamond in substantially the position shown in full lines in Figure 1, that is to say, with the point lying in a plane containing the axes of the cam and grinding wheel. In this position the simultaneous movements of the slides 5 and 12 in directions at right angles to each other under the influence of the lead screw 9 and cam 13 respectively, will cause the diamond to form, the rotating wheel 6 with a series of annular serrations or cutting edges hav-

ing a profile of substantially true thread form. The cam determines the depth component of the form and the lead screw the pitch component. After this primary dressing of the wheel, the plate 15 carrying the slide 12 and diamond carrier 11 is given an angular adjustment in one direction about the axis of the cam, by means of the handle 17, as represented in one of the dotted line positions in Figure 1, and more clearly in Figure 6. When the wheel is again dressed with the diamond in the new angular position in relation to the cam 13, an interference takes place between the diamond and one flank of the serrations on the wheel and a certain amount of material is removed therefrom. At the end of this second dressing the plate carrying the slide and diamond carrier is given an angular movement in the reverse direction to an equal extent in relation to the cam. The wheel is now again dressed when the interference between the diamond and wheel results in a similar removal of material from the other flank of the serrations. This process is repeated at increasing angular positions of the tool carrier equally in both directions until the angular position is such that the point of the diamond is clear of the serrations. The result produced is represented in Figure 7 in which the cross-sectional shape of the serrations produced by the primary dressing is shown in dotted lines and the final shape as produced by the subsequent dressing operations in full lines. The effect of the subsequent dressings, as will be seen, is to remove material from the flanks of the serrations in a progressive manner from the root to the crest.

If a grinding wheel having annular serrations formed or dressed in the manner above described is now transferred to its grinding position with respect to the work, as shown in dotted lines at the left-hand of Figure 1, and whilst rotated is traversed through the latter with the proper feed it will produce an internal screw thread which is a closer approximation to the ideal true thread form than would be obtained from the same wheel if the above described dressing operation had ceased at the end of the primary dressing.

If in dressing the wheel in the manner above described the wheel is mounted to rotate about an axis at right angles to the helix of the required screw thread the result will be to form a grinding wheel in which the positions of the effective portions of the several serrations vary, progressively from a position near the root at each end of the wheel to a position near the crest at the middle of the wheel. The wheel will also be of a more or less concave shape in cross-section at the root and crests of the serrations.

In the application of the present invention in the formation of grinding wheels of the kind herein referred to for use in external grinding operations, the position of the point 16 of the dressing tool with respect to the cam 13 will be substantially as shown in Figure 8 and 9, that is to say, the position of the diamond point with respect to the rotational axis of the cam when the latter is at its peak position with respect to the stylus on the slide must be adjusted until the distance between the diamond point and the axis of the cam is equal to the major radius of the work-piece. When this adjustment has been made the wheel is dressed in substantially the same manner as above described with reference to wheels for internal grinding operations with similar results on the cross-sectional

form of the serrations and on their effective diameters.

We claim:

1. Apparatus for forming and dressing grinding wheels used for form-grinding operations, comprising a slide, means for moving the same in a direction substantially parallel with the rotational axis of the grinding wheel, a second slide capable of angular adjustment upon the first slide about a fixed axis, a dressing tool adjustably mounted on said second slide, a cam rotatable about said fixed axis and adapted to cause the second slide to move towards and away from the axis of the grinding wheel irrespective of the angular position of said second slide, the movement of the first slide and the movement of the second slide under the influence of the cam being simultaneous and of such relative and respective extent as in combination with angular adjustment of said second slide about the axis of the cam will produce the required form in the grinding wheel.

2. Apparatus for forming and dressing grinding wheels used for form-grinding operations, comprising a slide, means for moving the same in a direction substantially parallel with the rotational axis of the grinding wheel, a second slide capable of angular adjustment upon the first slide about a fixed axis, a dressing tool adjustably mounted on said second slide, a cam rotatable about said fixed axis and adapted to cause the second slide to move towards and away from the axis of the grinding wheel irrespective of the angular position of said second slide, the distance between the point of the dressing tool and the rotational axis of the cam when the latter is at its peak position with respect to the second slide being equal to the core radius of the work-piece in the case of internal thread grinding operations and to the major radius of the work-piece in the case of internal thread grinding operations.

3. A machine for form-grinding operations comprising a fixed bed, a headstock slidably mounted thereon, a lead-screw for moving said headstock, a grinding wheel head arranged for movement to bring the grinding wheel into and out of its operative positions with respect to a work-holder and a wheel dressing attachment carried by said headstock, said attachment comprising a cam rotatably mounted in said headstock and a slide carrying a dressing tool and adapted for movement towards and away from the axis of the grinding wheel under the influence of said cam, said slide also having an angular adjustment about the rotational axis of the latter, the movements of said headstock and slide under the influence of the lead-screw and cam respectively for wheel dressing purposes being simultaneous and of such relative and respective extent as to cause the dressing tool when moved from one position to another about the axis of the cam to generate the required form in the grinding wheel.

4. Dressing means for grinding wheels wherein the wheel is mounted for rotation on a machine bed, comprising a main slide mounted on said bed adjacent said grinding wheel for linear movement towards and away from said wheel in a direction parallel to the rotational axis thereof, and means for producing such linear movement, in combination with a tool carrying slide mount-

ed on said main slide for reciprocation at right angles to the linear movement thereof and to the rotational axis of said wheel, said tool carrying slide being disposed for angular adjustment about

5 an axis parallel to the rotational axis of said grinding wheel, and means for causing reciprocation of said tool carrying slide irrespective of its angular position about said axis comprising a cam rotatable about the axis of angular adjustment of said tool carrying slide and in operative engagement therewith to cause reciprocation thereof.

5. A device of the character described comprising a main slide mounted for linear movement, 15 and a tool carrying slide mounted on said main slide for reciprocation in a transverse direction, said tool carrying slide being also disposed for angular adjustment about a linear axis, in combination with a cam mounted on said main slide for rotation about the axis of angular adjustment of said tool carrying slide and in operative engagement therewith to cause reciprocation of said slide during linear movement of said main slide irrespective of the angular position of said tool carrying slide.

6. The method of using a dressing tool to dress a grinding wheel having a series of annular serrations on its radial peripheral operating face, comprising rotating said wheel, and during such 20 rotation traversing said tool across the operative face of said wheel while maintaining the tool in a fixed position of angular adjustment about an axis parallel to the axis of said wheel, and simultaneously reciprocating said tool at right angles to the axis of said wheel in such a manner as to form the serrations thereof into true thread form, and thereafter, during continued rotation of said wheel, while fixedly maintaining said tool in a different position of angular adjustment 25 about said axis parallel to the axis of said wheel, again traversing said tool across said wheel while simultaneously reciprocating said tool in such manner that the reciprocating movements are of the same extent and fall in the same axial positions relative to said wheel respectively as during 30 said first traverse.

7. Dressing means for grinding wheels for grinding screw-threads in cylindrical faces of work-pieces, said dressing means being of the 35 type wherein the wheel is mounted on a machine bed for rotation about a relatively fixed axis and comprising a main slide mounted on said bed for linear movement in a direction parallel to said relatively fixed axis and means for causing such movement, in combination with a dressing tool, an auxiliary slide carrying said dressing tool and mounted on said main slide for oscillation about an axis parallel to said relatively fixed axis and disposed for reciprocation in a radial direction 40 relative to the path of oscillation thereof, the distance between the point of said dressing tool and the axis of oscillation when said tool point is at the extreme end of its reciprocatory movement away from the axis of oscillation being 45 substantially the same as the length of the radius of the circle defined by the crests of the threads of the work-piece, and automatic means for causing such reciprocation of said auxiliary slide and said dressing tool during movement of the main slide and in coordination therewith.

STANLEY JAFFA HARLEY.

JOHN ERNEST WAINWRIGHT.
